E. JABS

BOTTLE CAPPING MACHINE

Filed July 14, 1925

Patented July 5, 1927.

1,634,363

UNITED STATES PATENT OFFICE.

EDWARD JABS, OF CHICAGO, ILLINOIS.

BOTTLE-CAPPING MACHINE.

Application filed July 14, 1926. Serial No. 122,425.

This invention relates to certain novel improvements in bottle capping machines and more particularly to a holding device for a bottle to be capped.

5 The present invention has for its principal object the provision of a holding device of this character operatively associated with a bottle capping machine and operable by engagement with a portion of a bottle to be capped for holding the bottle in alignment with the capper of the bottle capping machine and shiftable in a direction to dispose the cap, loosely positioned at the mouth of the bottle, in aligned position with the capper.

10 A subsidiary object of the invention is the provision of a holding device permitting quick manual disposition of the cap and bottle into alignment from and into capping position.

15 A further object of the invention is the provision of a device of this character which will be highly efficient in use and economical in manufacture.

20 Other objects will appear hereinafter.

25 The invention consists in the combination and arrangement of parts to be hereinafter described and claimed.

The invention will be best understood by reference to the accompanying drawing illustrating the preferred form of my invention, and in which:

30 Fig. 1 is a typical side elevational view illustrating a bottle in operative association with a capping machine.

35 Fig. 2 is a fragmentary sectional detail view of the same taken substantially on line 2-2 of Fig. 1.

40 Fig. 3 is a sectional detail view taken substantially on line 3-3 of Fig. 1.

45 Fig. 4 is a sectional detail view similar to that illustrated in Fig. 3 showing certain elements of the holding device disposed in an inoperative position.

50 Fig. 5 is a fragmentary sectional detail view taken substantially on line 5-5 of Fig. 2.

55 Fig. 6 is a perspective view of one of the supporting plates embodied in the invention.

Fig. 7 is a perspective view of a base plate 50 embodied in the invention.

In the drawing I have illustrated a bottle capping machine with which my improved bottle holding device is associated. The capping mechanism includes a base foot 10 formed as an integral part of a standard 11 substantially T-shaped in cross section as

illustrated in Fig. 3 and defining a substantially goose shaped upper end portion 12, Fig. 1, bifurcated as at 13 to define oppositely disposed ears 14.

60 Disposed between the ears 14 is a cam head 15 formed as an integral part of an operating handle 16, Fig. 1. The cam head 15 is mounted eccentrically with respect to a pintle pin 17 which pivotally connects the cam head to the ears 14, Fig. 2.

65 The goose shaped end portion 12 defines a cylinder 18 within which is a reciprocatory plunger 19, Fig. 2. The plunger 19 rotatably carries at its upper end portion 20, through the medium of a pintle pin 21, a roller 22, Fig. 2, which is adapted for engagement with the cam edge 23 of the cam head 15, Fig. 1. The plunger 17 is yieldably urged into its uppermost position as 70 illustrated in Fig. 2, within the cylinder 18, through the medium of a spring member 24, Fig. 2, having one end portion 25 connected to the pintle 17 as at 26 and an opposite end portion 27 connected to the pintle 21 as at 27.

75 The lower end portion of the plunger 17 defines a substantially cap shaped capper 28 which is adapted to operate upon a cap 29 in a manner hereinafter set forth.

80 Confined in the capper 28, Fig. 2, is a cushioning element 30 which is adapted to provide yieldable bearing engagement between the cap 29 and the capper 28. This cushioning element in the present instance 85 is preferably formed of rubber or other compressible material.

85 The capper 28 is adapted to be disposed in alignment with the central point 31 of a mouth 32 defined by a lateral extension 33, Fig. 4, formed as an integral part of the standard 11 intermediate the end portions thereof.

90 To this lateral extension 33 I shiftable and pivotally associate my improved bottle holder generally indicated at A, Fig. 1. This bottle holder A defines a base plate 34 which is substantially U-shaped in plan view, Fig. 7, to define a mouth 35 which is adapted under certain conditions to coincide with the mouth 32 defined by the lateral extension 33. This base plate 34 defines an extension 36 comprising an elongate slot 37, Fig. 7, for the passage of a pintle screw 38 including a nut 39, carried 100 by the lateral extension 33. Inwardly of the outer end portion 40 of the extension 36

and on opposite sides thereof and formed integral with this extension are stop lugs 41 adapted under certain conditions for engagement with adjacent end portions 42, 5 Fig. 3, of segmental supporting plates 43 arcuated to conform to the shape of the arcuated limb portions 44 of the base plate 34 defining the mouth 35.

The inner edge portions 45 of the supporting plates 43 are normally, when in supporting position, disposed inwardly of the edge portion 46 of the base plate 34 for reasons hereinafter understood.

The supporting plates 43 are oscillatorily connected intermediate their end portions 42 and 42', through the medium of pintle pins 48, Fig. 4, to the limb portions 44 of the base plate 34 whereby the supporting plates 43 may be oscillated to dispose the end portions 42 from and into engagement with the stop lugs 41 for reasons hereinafter understood.

As shown in Fig. 1, when the base plate 34 is swung in a direction to dispose the central point 31 of the mouth 32 in alignment with the capper 28 the limb portions 44 of the base plate will be disposed upon adjacent portions of the extension 33 contiguous the mouth 32 thereby conveniently 30 supporting the bottle holder in operative capping position.

The operation of the invention is as follows.

To cap a bottle 29' the usual cap 29 is disposed in a position to close the mouth of the bottle. The bottle 29' with the cap 29 in this position is firmly grasped by one hand and disposed in supporting relation with the supporting plates 43 in the following manner:

When the supporting plates 43 are in an inoperative position the end portions 42 will be disposed inwardly of the stop lugs 41, Fig. 4 with the base plate 34 swung in an outward direction from the extension 33. The bottle is now manually manipulated to dispose the neck portion 30' thereof into contact with adjacent edge portions 31' of the edge portions 44. By lightly striking 50 the neck portion 30' of the bottle 29' against the edge portions 31' the supporting plates 43 will rotate in a direction to dispose the end portions 42 into engagement with the stop lugs 41. When the end portions 42 are disposed in engagement with the stop lugs 41 the end portions 42' of the supporting plates 43 will move inwardly toward each other to dispose the edge portions 45 of the supporting plates 43 into engagement 55 with the neck portion 30' of the bottle 29' beneath a beading 32'. The bottle is firmly held in position to dispose the end portions 42 into engagement with the stop lugs 41 and is caused to gently act upon the supporting plates 43 and to move in a direction

to pivot the base plate 34 in a direction to dispose the mouth 35 thereof over and concentric with the mouth 32. The supporting plates 43 when disposed in this position will effectively support the bottle and its cap 70 in capping position to be manipulated upon by the capping machine in the following manner.

To attach the cap 29 to the bottle 29' the operating handle 16 is pivoted in a downward direction about the pintle pin 17 to cause the cam edge 23 of the cam head 17 to act upon the roller 22 and urge downward movement of the plunger 19. As this plunger 19 moves in a downward direction 80 the capper 28 is brought into contact with the cap 29 and operates upon this cap 29 to turn the flange 33' of the cap 29 inwardly beneath a beading 34' included as a part of most approved bottles. 85

After the cap has been attached to the bottle 29' the bottle 29' being firmly grasped in the hand is drawn in an outward direction from the standard 11 to bring the neck portion 30' into contact with the edge portions 45 of the supporting plates 43 to disengage the supporting plates from supporting position with respect to the neck 30' of the bottle and for pivoting the base plate 34 in a direction to dispose the mouth 35 95 thereof from coinciding position with respect to the mouth 32. After this has been accomplished the bottle, being free from engagement with the supporting plates 43 can be readily removed. 100

From the above description it will be manifest that the operation of the supporting plates 43 into and from supporting position with respect to the bottle is accomplished by engagement of the neck portion 105 of the bottle with the edge portions 31' and 45.

By the provision of the elongated slot 37 it will be manifest that should the neck portion of the bottle 29' be disposed from the longitudinal axis of the bottle the base plate 34 can be shifted, by action of the bottle 29', in a direction to dispose the neck portion of the bottle with the cap 29 thereon in proper alignment with the capper 28. 110

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims. 120

Having thus described my invention, what I claim as new and desire to secure by Letters Patent is:

1. The combination with a capping machine which includes a capping element,

means for operating said capping element, of means for holding a bottle and a cap thereon in position to be operated upon by said capping element, said means including 5 a base plate pivotally associated with the capping machine, and supporting members pivotally supported by the base plate and operable upon engagement with a portion of the bottle for movement into supporting 10 engagement with respect to the bottle.

2. The combination with a capping machine which includes a capping element, means for operating said capping element, of means for supporting a bottle and a cap 15 thereon to be operated by said capping element, said means including a base plate pivotally associated with the capping machine, supporting members pivotally supported by the base plate and operable upon engagement 20 with a portion of the bottle for movement into and from supporting engagement with respect to the bottle, and stop lugs formed as an integral part of the base plate and serving to limit movement of the supporting 25 members when moved into supporting engagement with the bottle.

3. The combination with a capping machine which includes a capping element, means for operating said capping element, of means for supporting a bottle and a cap 30 thereon to be operated upon by the capping element, said means including a base plate pivotally supported by the capping machine and substantially U-shaped defining a mouth 35 for the accommodation of a neck portion of the bottle, segmental supporting plates pivotally connected to the base plate and movable into and from engagement with a portion of the bottle for supporting the bottle and the cap in position to be operated 40 upon by the capping element.

4. The combination with a capping machine which includes a capping element, means for operating said capping element, of means for supporting a bottle and a cap 45 thereon to be operated upon by the capping element, said means including a base plate pivotally supported by the capping machine

and substantially U-shaped defining a 50 mouth for the accommodation of a neck portion of the bottle, segmental supporting plates pivotally connected to the base plate and movable into and from engagement 55 with a portion of the bottle for supporting the bottle and the cap in position to be operated upon by the capping element, and stop lugs carried by the base plate and serving to limit pivotal movement of the supporting plates from supporting engagement 60 with respect to the bottle.

5. The combination with a capping machine including a standard, a lateral extension formed as an integral part of the standard, a capping element, and means for operating said capping element, of a bottle holding device for supporting a bottle and a cap 65 in position to be operated upon by the capping element, said device including a base plate, means pivotally and shiftably associating the base plate with the lateral extension, supporting elements pivotally connected to the base plate and operable upon engagement with a portion of the bottle for movement into and from supporting engagement 70 with respect to the bottle, and stop lugs carried by the base plate and serving to limit movement of the supporting elements into engagement with the bottle.

6. The combination with a capping machine including a standard, a lateral extension 75 formed as an integral part of the standard, a capping element, and means for operating said capping element, of a bottle holding device for supporting a bottle and a cap in position to be operated upon by the capping element, said device including a base plate, means pivotally and shiftably associating the base plate with the lateral extension, and supporting elements pivotally connected to the base plate and operable upon 80 engagement with a portion of the bottle for movement into and from supporting engagement 85 with respect to the bottle.

In testimony whereof I affix my signature.

EDWARD JABS.
